WASHING STRIP BRUSH

Alfred Steiner, Brooklyn, N. Y.

Application February 1, 1940, Serial No. 316,781

1 Claim. (Cl. 15—222)

This invention relates to new and useful improvements in a washing strip brush.

More specifically, the invention proposes the construction of a strip brush characterized by a sheet of soft flexible material having a plurality of fibers extending therefrom in a manner to form a brush for the purpose of washing one's back and other parts as the strip is drawn thereacross.

Still further it is proposed to loop the groups of fibers over certain of the threads forming the strip of material in a manner so that the adjacent threads will act to securely hold the groups of fibers in position.

Still further it is proposed to arrange the fibers in differently shaped groups along the central area of the sheet of flexible material.

Still further it is proposed to provide additional layers of material superimposed upon said sheet of flexible material and through which the fibers extend in a manner to hold the fibers at right angles to the sheet of material, and which are adapted to be removed when the fibers become worn away in a manner to increase the life of the brush.

A further object of this invention proposes to form the sheet of flexible material in the form of a glove having the fibers extended from one side thereof and which is engageable upon one's hand in a manner to be used for washing other portions of the body.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a back view of a person using a washing strip brush in accordance with this invention.

Fig. 2 is an enlarged perspective view of the brush per se.

Fig. 3 is a sectional view on the line 3—3 of Fig. 2.

Fig. 4 is a plan view of a brush constructed in accordance with a modification of the invention.

Fig. 5 is a view similar to Fig. 4 but illustrating a further modification of the invention.

Fig. 6 is a perspective view similar to a portion of Fig. 2 illustrating a still further modification of the invention.

Fig. 7 is a sectional view taken on the line 7—7 of Fig. 6.

Fig. 8 is a perspective view of a washing brush

glove constructed in accordance with this invention.

The washing strip brush, according to this invention, includes a sheet of soft flexible material 10 woven of warp threads 10^a and weft threads 10^b. These threads are preferably of sisal or the like material, and while being soft is extremely coarse in nature. This flexible material is adapted to form the base or back of the brush.

Fibers 11 forming the bristles of the brush are looped under certain of the threads and have their ends adjacent each other above the flexible material at a localized area thereof. These fibers are preferably located at the center of the sheet of material 10. As shown in Fig. 3 the fibers 11 are arranged in groups and are preferably looped about every other weft thread 10^b of the sheet of material. The other weft threads 10^b and the warp threads 10^a are adapted to engage the sides of the groups of fibers for securing each of the groups in position upon the weft threads about which it is looped.

The ends of the strip of flexible material are provided with a means for permitting the same to be conveniently grasped to move the same laterally across one's back when engaged therearound. This means comprises handle straps 12. These handle straps 12 are preferably U-shaped and have the ends of their arms secured to opposite sides of each of the ends of the strip of material 10 by means of stitches 13.

The operation of this form of the invention is as follows:

As shown in Fig. 1 the sheet of soft flexible material is engaged across one's back with the fibers 11 directed inwards. The handle straps 12 are then taken in the hand and are used for imparting a lateral motion to the sheet of material by alternately pulling upon the handles.

According to the modification of the invention shown in Fig. 4 the construction of the washing strip brush is similar to that previously described except that the fibers 11 are arranged in spaced vertically extending groups 11^a, 11^b and 11^c at the central area of the sheet of flexible material 10. In other respects this form of the invention is similar to the previous form and like parts are designated by the same reference numerals.

According to the modification of the invention shown in Fig. 5 the construction of the strip brush is also similar to that previously described except that the fibers 11 are arranged in spaced laterally extending groups 11^d and 11^e. In other respects this form of the invention is similar to the previous form.

According to the modification of the invention shown in Figs. 6 and 7 the construction of the washing strip brush is similar to that previously described except that the fibers 11' are longer than the fibers previously described, and a means is provided for holding them in a right angular position relative to the sheet of flexible material 10' and which is adapted to be removed as the ends of the bristles become worn for increasing the life of the brush. This means comprises superimposed sheets of material 10^{aa} and 10^{bb} arranged upon the side of the sheet of material 10' from which the groups of fibers 11' extend. These fibers 11', as shown in Fig. 7 are also extended around certain of the weft threads of these layers and similar to the arrangement shown relative to the weft threads of the sheet of flexible material 10'.

The layer 10^{bb} is securely attached to the layer 10^{aa} at its edges by means of basting stitches 14. The layer 10^{aa} is secured to the sheet of material 10' by means of additional basting stitches 15. As the fibers 11' become worn away and it is desired to increase the length thereof, it is merely necessary to cut the stitches 14 and remove the layer 10^{bb}. This will increase the length of the fibers 11' and the layer 10^{aa} will remain securely in position upon the sheet of material 10'.

As the fibers 11' become still shorter it is merely necessary to remove the layer 10^{aa} to further increase the length thereof. In other respects this form of the invention is similar to the previous form.

According to the modification of the invention shown in Fig. 8 the strip brush is in the form of a groove for engagement upon one's hand for washing other portions of the body. More specifically, the strip of soft flexible material 10' is doubled upon itself and the edges thereof are securely attached together by means of stitches

15. The groups of fibers 11' extend from one face of the sheet of material 10'.

The sides of the adjacent ends of the strip of material 10' are secured together by means of pieces of cloth material 17. These pieces of cloth material 17 have their ends secured to the superimposed sides of the sheet of material 10' by means of stitches 18. These strips of cloth material 17, in addition to securing these ends together, permit the overall diameter thereof to be greatly increased for providing an enlarged entrance for one's hand to permit the same to be conveniently engaged between the adjacent faces of the sheet of material in a manner to engage the glove upon one's hand. In other respects this form of the invention is similar to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a washing strip brush having a cloth back with a group of relatively long fibers projected beyond the top face of said cloth back forming bristles, warp and weft threads woven into a sheet of soft flexible material superimposed upon said sheet of material and having the ends of said fibers extending upwards between the threads of said upper sheet of material for reducing the operative length of said bristles, and means for releasably attaching said sheets of material together, whereby the life of said brush may be increased when the ends of said bristles become worn away by removing said top sheet of material to increase the operative length of the bristles.

ALFRED STEINER.
